(57) **CLAIM**

The ornamental design for a freestanding waterfall, as shown and described.

DESCRIPTION

FIG. 1 is front view of a freestanding waterfall, showing my new design;

FIG. 2 is a rear view thereof;

FIG. 3 is a right side view thereof;

FIG. 4 is a left side view thereof;

FIG. 5 is a top plan view thereof;

FIG. 6 is a bottom view thereof; and,

FIG. 7 is a perspective view thereof.

The dotted lines depicted in FIG. 2 illustrate the functional components of the waterfall and have been shown for illustrative purposes only and form no part of the claimed design.
